ADJUSTABLE SELF-CENTERING ROLL
Frank W. Butscher, Pittsburgh, Pa., assignor to United
States Steel Corporation, a corporation of New Jersey
Filed Mar. 24, 1959, Ser. No. 801,627
10 Claims. (Cl. 226—192)

This invention relates to a self-centering roll and more particularly to a self-centering roll of the type disclosed in the patents to Lorig Nos. 2,593,158 and 2,817,940. The rolls disclosed in these patents depend upon deflection of their end sections. In designing such rolls the tension to be applied to the roll by the strip passing thereover is an important factor in determining the centering action. The rolls shown in the above mentioned patents do not have any means for adjusting the amount of deflection which can take place under variable strip tensions. The patent to Lorig No. 2,692,773 discloses a roll having means for adjusting the deflection. However, this adjustment is dependent upon a plurality of tension bolts which must be individually adjusted to a common tension. This construction is expensive and the adjustment is difficult.

It is therefore an object of my invention to provide a self-centering roll which is provided with means for readily adjusting the amount of roll deflection.

This and other objects will be more apparent after referring to the following specification and attached drawings, in which:

FIGURE 1 is a sectional view of the preferred embodiment of my invention;

FIGURE 1a is an enlarged view of a portion of FIGURE 1;

FIGURE 2 is a view taken on the line line II—II of FIGURE 1 with parts broken away and shown in section; and

FIGURE 3 is a sectional view of another embodiment of my invention.

Referring more particularly to FIGURES 1, 1a and 2, the reference numeral 2 indicates coaxially opposed rotatable hollow cylinders over which a strip S passes in a direction transverse to the axes of the cylinders. Each of the cylinders 2 is provided with a radial web 4 at its outer end which is attached to a sleeve 6 in any manner providing for axial adjustment. As shown, this connection is a universal joint 8 but the web 4 could be attached directly to a ring 10 mounted on the sleeve 6. The universal joint 8 consists of three rings 10, 12 and 14. The ring 10 is attached to the sleeve 6 by means of a set screw 16. The outer ring 14 is welded to the web 4. The center ring 12 is pivotally attached to the outer ring 14 by means of diametrically opposed pins 18 and to the inner ring 10 by means of diametrically opposed pins 20 arranged at 90° from the pins 18. A locking pin 22 passes through each of the pins 18 and a similar locking pin 24 passes through each of the pins 20. Sufficient clearance is left between rings 10 and 12 and between rings 12 and 14 to permit tilting movement therebetween. A radial web 26 is fastened to the adjacent ends of the rims 2 and is provided with a bronze sleeve or bearing 28 held in position by means of set screws 30. Each of the sleeves 6 has a frusto-conical end 32 which is received in the opening in bushing 28. The sleeves 6 are hollow to receive a shaft 34 and are held in position thereon by means of set screws 38. This construction also enables the surface of both cylinders 2 to be machined after assembly.

The operation of the self-centering roll is essentially the same as that shown in the above mentioned patents with the universal joints 8 serving to compensate for tilting as shown in my copending application Serial No. 799,209, filed March 13, 1959, entitled Self-Centering

2

Roll. When it is desired to change the amount of deflection of the cylinders the set screws 16 and 38 are loosened and the sleeves 6 moved axially to the desired position after which the set screws 16 and 38 are tightened.

In the embodiment of my invention shown in FIGURE 3, each of the cylinders 2' is provided with a frusto-conical inside surface 40 and each sleeve 6' is provided with a radial web or flange 42 at its inner end. The construction is otherwise the same as that of the roll of FIGURE 1 and the adjustment for variable tension is essentially the same as that of the roll of FIGURE 1. The set screws 16 and 38 are loosened and the sleeves 6' are moved axially so as to vary the peripheral space or clearance between the surface 40 and the web 42. Thus, in each embodiment a peripheral clearance is provided between an inner web and a frusto-conical surface, the amount of clearance being variable by moving a sleeve axially.

While two embodiments of my invention have been shown and described, it will be apparent that other adaptations and modifications may be made without departing from the scope of the following claims.

I claim:

25. 1. Apparatus for positioning a moving object comprising a pair of coaxially opposed rotatable hollow cylinders over which the object passes in a direction transverse to the axes of the cylinders, each of said cylinders having inner and outer ends with the inner ends adjacent each other, means supporting the outer ends of said cylinders, means extending through said cylinders coaxial therewith and arranged to provide a peripheral space to permit limited deflection of the adjacent ends of said cylinders, and means for changing the width of said peripheral space to vary the amount of deflection of the adjacent ends of said cylinders.

40. 2. Apparatus for positioning a moving object comprising a pair of coaxially opposed rotatable hollow cylinders over which the object passes in a direction transverse to the axes of the cylinders, each of said cylinders having inner and outer ends with the inner ends adjacent each other, means supporting the outer ends of said cylinders, means extending through said cylinders coaxial therewith, means extending radially between said second named means and said cylinders, said last named means being of such dimensions as to provide a peripheral space to permit limited deflection of the adjacent ends of said cylinders, and a frusto-conical surface on one of said second named means and its associated cylinder, said second named means being movable axially to change the width of said peripheral space to vary the amount of deflection of the adjacent ends of said cylinders.

55. 3. Apparatus for positioning a moving object comprising a pair of coaxially opposed rotatable hollow cylinders over which the object passes in a direction transverse to the axes of the cylinders, each of said cylinders having inner and outer ends with the inner ends adjacent each other, means supporting the outer ends of said cylinders, said means including a universal coupling, means extending through said cylinders coaxial therewith and arranged to provide a peripheral space to permit limited deflection of the adjacent ends of said cylinders, and means for changing the width of said peripheral space to vary the amount of deflection of the adjacent ends of said cylinders.

70. 4. Apparatus for positioning a moving object comprising a pair of coaxially opposed rotatable hollow cylinders over which the object passes in a direction transverse to the axes of the cylinders, each of said cylinders having inner and outer ends with the inner ends adjacent each other, means supporting the outer ends of said cyl-

inders, said means including a universal coupling, means extending through said cylinders coaxial therewith, means extending radially between said second named means and said cylinders, said last named means being of such dimensions as to provide a peripheral space to permit limited deflection of the adjacent ends of said cylinders, and a frusto-conical surface on one of said second named means and its associated cylinder said second named means being movable axially to change the width of said peripheral space to vary the amount of deflection of the adjacent ends of said cylinders.

5. Apparatus for positioning a moving object comprising a pair of coaxially opposed rotatable hollow cylinders over which the object passes in a direction transverse to the axes of the cylinders, each of said cylinders having inner and outer ends with the inner ends adjacent each other, a radial web at the outer end of each of said cylinders, a shaft extending through said cylinders coaxial therewith, a pair of coaxially opposed rotatable sleeves adjustably mounted on said shaft one within each cylinder, a universal joint extending between and attached to said radial web and said sleeve at the outer end of each cylinder, means extending radially between each of said sleeves and its associated cylinder, said means being of such dimensions as to provide a peripheral space to permit limited deflection of the adjacent ends of said cylinders, and radially opposed cooperating surfaces forming said peripheral space, one of said cooperating surfaces being frusto-conical, said sleeves being movable axially to change the width of said peripheral space to vary the amount of deflection of the adjacent ends of said cylinders.

6. Apparatus for positioning a moving object comprising a pair of coaxially opposed rotatable hollow cylinders over which the object passes in a direction transverse to the axes of the cylinders, each of said cylinders having inner and outer ends with the inner ends adjacent each other, a radial web at the outer end of each of said cylinders, a shaft extending through said cylinders coaxial therewith, a pair of coaxially opposed rotatable sleeves adjustably mounted on said shaft one within each cylinder, means supporting said radial web on the associated sleeve, means extending radially between each of said sleeves and its associated cylinder, said last named means being of such dimensions as to provide a peripheral space to permit limited deflection of the adjacent ends of said cylinders, and radially opposed cooperating surfaces forming said peripheral space, one of said cooperating surfaces being frusto-conical, said sleeves being movable axially to change the width of said peripheral space to vary the amount of deflection of the adjacent ends of said cylinders.

7. Apparatus for positioning a moving object comprising a pair of coaxially opposed rotatable hollow cylinders over which the object passes in a direction transverse to the axes of the cylinder, each of said cylinders having inner and outer ends with the inner ends adjacent each other, a radial web at the outer end of each of said cylinders, a shaft extending through said cylinders coaxial therewith, a pair of coaxially opposed rotatable sleeves adjustably mounted on said shaft one within each cylinder, means supporting said radial web on the associated sleeve, a radial web attached to each of said cylinders at the end adjacent the other cylinder, and a frusto-conical surface on the inner end of each sleeve, the inside diameter of each of said last named webs being greater than the diameter of the cooperating surface of said sleeve so as to provide a peripheral space to permit limited deflection of the adjacent ends of said cylinders, said sleeves being movable axially to change the width of said peripheral space to vary the amount of deflection of the adjacent ends of said cylinders.

8. Apparatus for positioning a moving object comprising a pair of coaxially opposed rotatable hollow cylinders over which the object passes in a direction transverse to the axes of the cylinders, each of said cylinders having inner and outer ends with the inner ends adjacent each other, a radial web at the outer end of each of said cylinders, a shaft extending through said cylinders coaxial therewith, a pair of coaxially opposed rotatable sleeves adjustably mounted on said shaft one within each cylinder, a universal joint extending between and attached to said radial web and said sleeve at the outer end of each cylinder, and a radial web attached to each of said cylinders at the end adjacent the other cylinder, a frusto-conical surface on the inner end of each sleeve, the inside diameter of each of said last named webs being greater than the diameter of the cooperating surface of said sleeve so as to provide a peripheral space to permit limited deflection of the adjacent ends of said cylinders, said sleeves being movable axially to change the width of said peripheral space to vary the amount of deflection of the adjacent ends of said cylinders.

9. Apparatus for positioning a moving object comprising a pair of coaxially opposed rotatable hollow cylinders over which the object passes in a direction transverse to the axes of the cylinders, each of said cylinders having inner and outer ends with the inner ends adjacent each other, a radial web at the outer end of each of said cylinders, a shaft extending through said cylinders coaxial therewith, a pair of coaxially opposed rotatable sleeves adjustably mounted on said shaft one within each cylinder, means supporting said radial web on the associated sleeve, a radial web attached to each of said sleeves at the end adjacent the other sleeve, and a frusto-conical surface on the inside of the inner end of each cylinder, the outside diameter of each of said last named webs being less than the diameter of the cooperating surface of said cylinder so as to provide a peripheral space to permit limited deflection of the adjacent ends of said cylinders, said sleeves being movable axially to change the width of said peripheral space to vary the amount of deflection of the adjacent ends of said cylinders.

10. Apparatus for positioning a moving object comprising a pair of coaxially opposed rotatable hollow cylinders over which the object passes in a direction transverse to the axes of the cylinders, each of said cylinders having inner and outer ends with the inner ends adjacent each other, a radial web at the outer end of each of said cylinders, a shaft extending through said cylinders coaxial therewith, a pair of coaxially opposed rotatable sleeves adjustably mounted on said shaft one within each cylinder, a universal joint extending between and attached to said radial web and said sleeve at the outer end of each cylinder, a radial web attached to each of said sleeves at the end adjacent the other sleeve, and a frusto-conical surface on the inside of the inner end of each cylinder, the outside diameter of each of said last named webs being less than the diameter of the cooperating surface of said cylinder so as to provide a peripheral space to permit limited deflection of the adjacent ends of said cylinders, said sleeves being movable axially to change the width of said peripheral space to vary the amount of deflection of the adjacent ends of said cylinders.
